UNITED STATES PATENT OFFICE

NAPOLEON B. DOUGLASS, OF BERKELEY, CALIFORNIA

REVERSIBLE DOOR MOUNTING

Application filed December 29, 1928. Serial No. 329,225.

This invention relates to a reversible door mounting such as is used in connection with recess or closet beds, and wherein a portion of the door opening is always obstructed by the overhang of the bed, such mounting permitting the door to be reversed in a manner to close the opening when the bed is out of the closet in position for use.

The object of the invention is to provide a mounting of this general character which can be economically manufactured and assembled without the necessity of fitting tracks or other attachments to the top or bottom sills. In connection with prior devices of this sort, which make use of tracks fastened to the sills of the doorway, it has been found that a great deal of labor is required to properly assemble and position these tracks, and that where metal frames are used for the doorway it is almost impossible to employ these tracks.

One form which my invention may assume is exemplified in the following description and illustrated in the accompanying drawing, in which

Fig. 1 shows a perspective view of a recess or closet fitted with a bed and door, the door mounting representing a preferred embodiment of my invention;

Fig. 2 shows a perspective view of the plate employed on the lower sill;

Fig. 3 shows a plan view in section of the upper portion of the door mounting;

Fig. 4 shows an elevation of the door and mounting;

Fig. 5 shows a plan view in section of the door and mounting in normal position, with the bed stored within the closet;

Fig. 6 shows a similar view with the door open so as to permit the bed to be swung out of the closet;

Fig. 7 shows a similar view of the bed outside of the closet and the door in reversed and closed position.

Referring in detail to the accompanying drawings, the closet or recess is indicated at 10 and is positioned with a door opening adapted to be closed by a door 11. A bed

12 or other article of furniture is mounted by means of pivots 13 on one of the jambs

of the door opening so as to be swung through the opening, the said bed being wider than the door opening and hence having a portion extending across the opening both when the bed is stored in the closet and when positioned outside for use.

The door is hingedly mounted upon a yoke-shaped member consisting of a vertical post 14 and top and bottom horizontal arms 15, the said arms being pivotally connected to the top and bottom sills of the door opening near the middle thereof. With such a mounting the door can be swung on its hinges from a closed position to a right angle position, as shown in Fig. 6, leaving space for the bed to be moved through the opening, and thereafter the door can be moved bodily into a reversed, closed position, as shown in Fig. 7, by reversing the position of the yoke-shaped member.

It is essential, however, that the door during this movement be controlled so as to simplify its operation and prevent it from striking the bed. This I accomplish by the following mechanism:

Secured to the door, preferably near the top, is a plate 16 on which are carried a vented cylinder 17 containing a piston 18, to which piston is connected a rod 19, said rod passing slidably through a guide 20. A link 21 is pivotally connected to the rod 19 and also to the post 14. A torsion spring 22 is provided for the end of the link, which connects with the post, said spring exerting a force tending to pull the door against the arms 15. When the door is closed, the piston will be at the farther end of the cylinder, as shown in Fig. 5, and when the door is opened, as shown in Fig. 6, the piston will be at the opposite end of the cylinder, the said piston and spring both acting to resist opening movement of the door, and thereby pulling the arms 15 against a stop member 23 arranged on the lower sill, thereby tending to keep the yoke member from swinging inwardly on its pivots.

In the open position of the door, a spring latch 24 on the plate 16 fits against a projection 25 on the rod 19, and holds the door at right angles to the arms 15. The door may

now be moved bodily into reversed position about the pivots of the arms 15, during which movement it is necessary to release it from the latch and allow it to gradually move towards the arms 15. However, on account of the resistance offered by the piston, the door will not swing rapidly on its hinges, so that very little manual effort is required to guide it at this time, the action being semi-automatic.

In the reversed position of the door, a spring catch 26 on the bottom of the plate 27 will press against the lower arm and restrain the yoke-shaped member from turning about its pivots. This catch 26 will function in a similar manner when the arms are in the opposite position against an extension 28 on the lower arm.

In the reversed position of the door, said door may be swung inwardly on its hinges as indicated in dotted lines in Fig. 7, so as to permit access to the closet.

Various changes in the construction and arrangement of the several parts herein shown and described may be employed without departing from the spirit of my invention as disclosed in the appended claims.

Having thus described my invention, what I claim as new and desire to secure by Letters Patent is:

1. A door having hinges at one edge, a swinging support for the hinges, reversible within the door opening so as to permit the door to be reversed and close the opening, and means forming a direct connection between the swinging support and the door, to control the latter and restrain its swinging movement during reversal of the support.

2. A door having hinges at one edge, a swinging support for the hinges, reversible within the door opening so as to permit the door to be reversed and close the opening, and means forming a direct connection between the swinging support and the door, to control the latter and restrain its swinging movement, whereby the door will be reversed during reversal of the support, and means to retain the swinging support in position during the time the door is being moved about its hinges in opening or closing the same.

3. The combination of a door and its opening, a portion of which opening is always obstructed, hinges at one edge of the door, a swinging support for the hinges, reversible within the door opening, and a yielding connection between the swinging support and the door to control the hinge movement of the door during reversal of the swinging support.

4. A door having hinges at one edge, a swinging support for the hinges, reversible within the door opening, and permitting the door to be reversed and close the opening, said support comprising an upright member having horizontal arms centrally pivoted in

the door opening, said upright member being adapted to lie adjacent either one of the jambs of the door opening, spring means tending to keep the door parallel with the arms, and a cylinder and piston forming a connection between the door and support and acting to restrain hinge movement of the door in either direction.

5. A door having hinges at one edge, a swinging support for the hinges, reversible within the door opening, and permitting the door to be reversed and close the opening, said support comprising an upright member having horizontal arms centrally pivoted in the door opening, said upright member being adapted to lie adjacent either one of the jambs of the door opening, spring means tending to keep the door parallel with the arms, a cylinder and piston forming a connection between the door and support, and acting to restrain hinge movement of the door in either direction, and means to yieldingly retain the swinging support in position where the arms are substantially parallel with the door opening.

6. A door having hinges at one edge, a swinging support for the hinges, reversible within the door opening, and permitting the door to be reversed and close the opening, said support comprising an upright member having horizontal arms centrally pivoted in the door opening, said upright member being adapted to lie adjacent either one of the jambs of the door opening, spring means tending to keep the door parallel with the arms, a cylinder and piston forming a connection between the door and support and acting a restrain hinge movement of the door in either direction, and a yielding latch device to retain the door in position substantially at right angles to the said arms.
